COIN DISPENSER

Louis C. McIlheran, 6123 Velasco St.,
Dallas, Tex. 75214

Filed Oct. 14, 1970, Ser. No. 25,478

Term of patent 14 years

Int. Cl. D31—Misc.

U.S. Cl. D52—4

Fig. 5

Fig. 4

Fig. 2

Fig. 3

Fig. 1

Fig. 6

FIG. 1 is a perspective view of the coin dispenser showing my new design;

FIG. 2 is a top plan view thereof;

FIG. 3 is a right side elevation view thereof;

FIG. 4 is a left side elevation view thereof;

FIG. 5 is a front elevation view thereof; and

FIG. 6 is a rear elevation view thereof.

The bottom of the coin dispenser is flat and of the same peripheral dimensions as the top.

I claim:

The ornamental design for a coin dispenser, as shown and described.
